UNITED STATES PATENT OFFICE.

CHARLES THOMAS MOORE, OF LANCASTER, OHIO, ASSIGNOR TO THE COLUMBUS GLASS COMPANY, OF LANCASTER, OHIO.

DEVICE FOR CAPPING OFF GLASS CYLINDERS.

1,101,033.

Specification of Letters Patent. Patented June 23, 1914.

Application filed September 29, 1913. Serial No. 792,370.

To all whom it may concern:

Be it known that I, CHARLES THOMAS MOORE, of Lancaster, in the county of Fairfield and State of Ohio, have invented certain new and useful Improvements in Devices for Capping Off Glass Cylinders; and I do hereby declare the following to be a full, clear, and exact description of the invention, such as will enable others skilled in the art to which it appertains to make and use the same.

My invention relates to an improvement in devices for capping-off glass cylinders, the objects being to provide improved means for holding the heating wire in contact with the cylinder, and for taking up the slack due to lengthening of the wire while heated.

A further object is to provide a construction wherein the entire circumference of the cylinder is exposed to contact with the wire.

With these and other objects in view my invention consists in the parts and combinations of parts and in the details of construction as will be more fully explained and pointed out in the claims.

In the accompanying drawings, Figure 1 is a view in side elevation showing my improvement applied to a glass cylinder; Fig. 2 is a view in section through the handle; Fig. 3 is a view of a modification, and Fig. 4 a view in section through the handle.

1 represents a frame, semi-circular in shape and provided adjacent its two ends, and approximately midway its ends, with the inwardly projecting fingers 2, 3 and 4. The fingers 2 and 4 are each provided with contact rollers or terminals 5, adapted to make contact with the cutting or capping-off wire 6, while the finger 3 is for properly spacing the frame 1 from the glass cylinder. The finger 3 is provided with an elongated slot 8 for the passage of the thumb screw 9 which latter adjustably locks the finger to the frame, and the finger 2 carrying a contact roller 5 is preferably slidingly mounted in frame 1 and packed up by a spring as shown.

The frame is made of nonconducting material and the fingers of conducting material. The frame is of a size to conform to a standard size cylinder. The cylinders as they are drawn, are approximately of the same diameter, and while they may vary slightly, or vary at different points throughout their lengths, such variations in size may

be taken care of by making the fingers 2 and 4 contact with the cylinder just above the greatest diameter of cylinders of the standard size, and by making two or more of the fingers adjustable as shown.

9^a is a handle preferably formed integral with the frame 1, and is of a size to be conveniently grasped by one hand of the operator, and 10 is a block mounted to slide in a slot in the handle and provided at one edge with rack teeth adapted to be engaged by the pawl 11, pivotally mounted on the handle. This block is preferably provided with tenons which rest and move in mortises 12 in the handle, so as to permit of the necessary movement of the sliding block 10, and is connected by pins at its lower end to two ends of the cutting or capping-off wire 7 which latter pass downwardly and cross under the terminal 5, in contact with each other and with the terminal 5 so as to form the cylinder cutting loop. The finger 4 carrying the terminal 5, may be provided with loops or guides 4^a for holding the wire in proper position with relation to the terminal 5, and the block 10 is provided with a finger hole by which it may be manipulated to let out or take up the wire whereby the size of the cutting or capping-off loop thereof will be increased or decreased.

13 and 14, are the current conducting wires, the latter of which leads to the switch 15 on frame 1, and from thence to the terminal 5 on finger 2 and is connected to the same, while the other wire 13, is connected with terminal 5 on finger 4.

In the operation of the device, the wire loop 7 is passed over the end of a cylinder to be capped or cut, and when properly positioned thereon, is drawn taut by a rearward pull on block 10, after which the frame 1 is moved, if necessary, to carry the terminal 5 on finger 2 into contact with the cutting-off wire 6, at a point approximately opposite the other terminal 5 so that the two terminals 5, engage the cutting off wire 6, approximately on the longest diameter of the cylinder. If when the parts are so placed, the switch 15 be closed, the current from the leading-in wire 14 will pass to the terminal 5 on finger 2, and as the latter is in electrical contact with the heating wire 6 at the far side of the cylinder, the current will divide, and passing around the wire 6 in both directions, heat the same sufficiently

- to crack the cylinder in the well known manner, and pass out through the terminal 5 on finger 4, and through the conductor 13 which is connected with said terminal.
- 5 When the parts are applied to a cylinder, the frame 1 is held properly spaced from the cylinder by the spacing finger 3, and the heating wire loop 6 is closed onto the cylinder by the sliding block 10, and is held 10 taut by the pawl 11. As the heating wire is continuous around the cylinder with its ends in contact, the entire circumference of the cylinder will be heated, thus avoiding the necessity of shifting the device in order 15 to complete the heating.
- In the construction shown in Figs. 3 and 4, I have made the frame 1^a, in two parts each of which is in the form of a half circle with a handle 9^a at one end. Each part 20 of the frame is provided adjacent its ends with terminal contacts 5^a and 5^b and the latter of which are preferably spring supported as in Fig. 1, so as to provide for cylinders of different sizes, and each also carries a section of the cutting off wire 6^a, each 25 of which is secured at one end to its respective terminal contact 5^b, and at its other end to pins on cross arm carried by the movable block 10^a mounted in a slot in one 30 handle section, each wire in its passage from contact 5^b to its cross arm, passing around or through and in contact with its terminal contact 5^a. The block 10^a is shown provided on one edge with ratchet teeth which are 35 adapted to be engaged by the pawl 11^a for locking the block against movement in a direction to loosen up the cutting off wire and is also provided with a finger hole for drawing the block outwardly. The current 40 conducting wire 14^a leads to the switch 15^a in one section and from thence to terminal contact 5^b on the same section of the frame, and the other wire 13^a is connected with the terminal contact 5^a of the other section of 45 the frame. The two sections of the frame are locked together by the clamp 16^a carried by one section and adapted to engage locking means 17^a on the other section. In applying the device to a glass cylinder, the 50 sections of the frame are disconnected and separated so as to permit them to be properly placed on a cylinder, and when so placed, the terminals 5^a will be in contact with each other, and the two terminals 5^b 55 will be in contact with each other, so that a current from conductor 14^a will pass from both terminals 5^b through the two wires 6^a to the terminals 5^a and from thence to conductor 13^a. I prefer to suspend both sections of the frame 1^a from a trolley 19 as 60 shown in Fig. 3, so that it can be readily moved from one position to another and remain suspended when not in use. While I have shown the ends of the cutting-off wire 65 secured to an adjustable block, it is evident that when a continuous wire is used, as in Fig. 1, it may be secured at one end to the handle and the slack taken up by wrapping the other end around the finger, as is now done with some of the capping-off devices 70 in use. Again in the construction shown in Fig. 3 the terminals 5^a and 5^b on one section make contact with the corresponding terminals on the other section, so that when the frame is applied to the cylinders, the two terminals 5^b 75 constitute one terminal, both for the conductor wire and also the heating wire loop and this is also true of the two terminals 5^a.
- It is evident that many slight changes 80 might be resorted to in the relative arrangement of parts shown and described without departing from the spirit and scope of my invention. Hence I would have it understood that I do not wish to confine myself to 85 the exact construction and arrangement of parts shown and described but
- Having fully described my invention what I claim as new and desire to secure by Letters-Patent, is:-
- 90
1. A capping off device for glass cylinders consisting of a frame shaped to conform to the cylinder and having oppositely disposed terminals adapted to rest opposite each other on opposite sides of the cylinder, heating means contacting with both of said terminals, means for taking up the slack in said heating means, a conductor for each of said terminals and a switch in one of said conductors.
- 100
2. A capping off device for glass cylinders consisting of a curved frame having inwardly projecting and oppositely disposed terminals, a conductor connected with each terminal, a switch forming a part of one conductor, and 105 a heating wire carried by the frame and contacting with both of said terminals.
- 110
3. A capping off device for glass cylinders comprising a frame curved to conform to the cylinder and having a handle at one end, and inwardly projecting terminals adjacent its two ends, the said terminals adapted to rest on opposite sides of the cylinder adjacent the greatest diameter of the latter, a conductor leading to each terminal, a heating wire loop carried by said frame and contacting with both of said terminals and means for taking up slack in the loop.
- 115
4. A capping off device for glass cylinders comprising a curved frame having a handle, and inwardly projecting terminals adjacent its two ends, a conductor leading to each terminal, a heating wire loop carried by said frame and adapted to make contact with both terminals, and a sliding block on said handle to which the wire loop is connected.
- 120
5. A capping off device for glass cylinders comprising a curved frame having a handle, and inwardly projecting terminals adjacent its two ends, one of said terminals being 125
- 130

adjustable, a conductor leading to each terminal, a heating wire loop carried by the frame and adapted to make contact with both terminals and a sliding block on said 5 handle to which both ends of the wire loop are connected.

6. A capping off device for glass cylinders comprising a curved frame, having a handle, and inwardly projecting terminals 10 adjacent its two ends, one of said terminals being adjustable, a conductor leading to each terminal, a switch forming a part of one of said conductors, a sliding block car-

ried by the handle, means for rocking the sliding block against movement and a heating wire connected to said sliding block and adapted to make contact with said projecting terminals. 15

In testimony whereof, I have signed this specification in the presence of two subscribing witnesses. 20
